McBesson

Attorney

UNITED STATES PATENT OFFICE.

JOHN SITKO, OF FORT WAYNE, INDIANA, ASSIGNOR OF ONE-THIRD TO LUDWIK SITKO
AND ONE-THIRD TO FRANCISZEK SITKO, BOTH OF FORT WAYNE, INDIANA.

RAIL-JOINT.

1,231,440.

Specification of Letters Patent. Patented June 26, 1917.

Application filed January 22, 1917. Serial No. 143,616.

To all whom it may concern:

Be it known that I, JOHN SITKO, a subject of the Emperor of Austria, residing at Fort Wayne, in the county of Allen and State of Indiana, have invented certain new and useful Improvements in Rail-Joints, of which the following is a specification.

This invention relates to certain new and useful improvements in rail joints.

10 The primary object of the invention is the provision of a joining means for railway rails whereby the rails are locked together in track formation without the necessity of employing any bolts, screws, spikes or other similar members which are adapted to work loose and become detached.

20 A further object of the device is the provision of an interlocking rail joint having a releasable securing means whereby the adjacent rails are readily secured and released while in longitudinal alinement with each other, the entire structure possessing great strength and serviceability under the varying traffic conditions of the railway line.

25 With these general objects in view and others that will appear as the nature of the invention is better understood, the same consists in the novel construction, combination and arrangement of parts hereinafter 30 more fully described, illustrated in the accompanying drawings, and then claimed.

35 In the drawing forming a part of this application and in which like designating characters refer to corresponding parts throughout the several views:—

Figure 1 is a side elevation of the device in its locked arrangement illustrated in connection with the adjacent end portions of railway rails, the securing means being 40 shown by dotted lines in its released position.

Fig. 2 is a horizontal longitudinal sectional view taken upon the line II—II of Fig. 1.

45 Figs. 3 and 4 are vertical transverse sectional views taken upon lines III—III and IV—IV respectively, of Fig. 1, and,

Fig. 5 is a slightly enlarged detail view through the engaging side of the securing 50 means.

It being understood that the present rail joint is designed for locking together the adjacent ends of railway rails in their operative arrangement, the same is herein illustrated in connection with the adjacent end

portions of rails 10 and 11 of the usual construction.

The contacting end portions of the rails 10 and 11 are complementally formed for interlocking arrangement, the terminal portion of the tread 12 of the rail 10 being removed and the web 13 thereof having its terminal portion 14 of slightly greater height than the main portion of the web and provided with a rectangular seat or notch 15 while grooves 16 are arranged in the base 17 of the rail 10 at the bottom of the web portion 13 of the said rail. The complementally formed end of the rail 11 provides a thickened terminal web portion 18 70 having a slot 19 therein formed with a terminal block 20, the web extension 14 of the rail 10 being adapted for insertion within the slot 19 with the block 20 resting within the notch 15 of said extension and with the 75 adjacent ends of the tread 12 of the rail 10 and the tread 21 of the rail 11 in substantial contact with each other.

The terminal portion of the base 22 of the rail 11 is cut-away providing free lower 80 edges 23 for the sides of the web portion 18 of the rail 11, which lower edges are adapted to seat within the opposite grooves of the base 17 of the rail 10 when the device is operatively arranged and at which times the 85 adjacent ends of the rail bases 17 and 22 are substantially in contact with each other. An enlargement forming opposite shoulders 24 is provided at the free end of the web 13 of the rail 10, the free ends of the sides of 90 the web portion 18 being substantially in contact with such shoulders when the rails are in their interlocked positions.

It will be understood that when the rails are assembled as shown in Fig. 1, without 95 the employment of the securing member 25 which is mounted upon the bases of the rails, the engaging ends may be readily released by moving the rail 11 vertically, thereby separating the same from the rail 10 while 100 the seating interlocking engagement of the rail 11 with the rail 10 is readily accomplished by reversing the said operation.

The aforementioned securing means is substantially U-shaped in cross-section having inwardly extending top flanges 26 adapted for overlying the opposite edges of the bases 17 and 22 of the rails, it being noted that the member 25 is slidably arranged upon the said rail bases within longi- 110

tudinal recesses 27 arranged in the outer edges of said bases, the ends 28 of said recesses forming stop shoulders for the longitudinal sliding movement of the member 25.

5 A spring latch 29 is carried within a socket 30 of one of the flanges 26 of the securing member, said latch adapted for seating within a keeper opening 31 in the base 22 of the rail 11 when the securing member 10 is in its released position as shown by dotted lines in Fig. 2 of the drawing. The latch 29 is adapted for springing in engagement within a similar keeper opening 32 in the base 17 of the rail 10 when the member 25 is 15 in its securing position overlying the adjacent end portions of the bases 17 and 22 and in which position it will be seen that it will be impossible to either elevate or lower one of the rails 10 and 11 relatively with 20 respect to the other or in other words, the rails cannot be separate, when the member 25 is in its securing position as shown in the drawing. A lateral extension of the socket 25 30 permits the latch 29 to be grasped or engaged by a convenient tool (not shown) for releasing the same from either of the keeper openings with which the same may be engaged. While said latch 29 is adapted for retaining the securing member 25 in place, 35 a lock bolt 34 may be provided through one of the flanges 26 for threaded engagement with an opening 35 in the base 22 of the rail 11 when desired to make the arrangement more secure. The bolt 34 may also be employed for retaining the member 25 in its inoperative position as shown by dotted lines 40 in Fig. 1 of the drawing for such purposes as transportation by threading the bolt 34 into a perforation 36 in the said base 22 of the rail 11.

The manner of assembling the rails formed as herein described has already been set forth and the complete operation of the device will now be apparent in view of the

foregoing description of the operation of 45 the securing member 25 and while the present embodiment of the device is believed to be preferable, minor changes may be made if desired without departing from the spirit and scope of the invention as claimed. 50

What I claim as new is:—

1. In combination with rails having the base flanges at the ends of said rails provided with marginal recesses, a securing member partially inclosing the bases of the 55 rails slidably mounted thereon within the said recesses and adapted to overlie the ends of the adjacent rail bases when the rails are in their assembled relations, the end portions of said bases being provided with keeper 60 openings, a spring latch carried by said securing means adapted for seating within one of said openings when the securing means is in its operative position and in the other of said openings when in its released position 65 inclosing the base of only one of said rails.

2. In combination with rails having the base flanges at the ends of said rails provided with marginal recesses, a securing member partially inclosing the bases of the 70 rails slidably mounted thereon within the said recesses and adapted to overlie the ends of the adjacent rail bases when the rails are in their assembled relations, the end portions of said bases being provided with 75 keeper openings, a spring latch carried by said securing means adapted for seating within one of said openings when the securing means is in its operative position and in the other of said openings when in its released position 80 inclosing the base of only one of said rails, and a locking bolt carried by said securing means adapted for adjustable engagement with one of said rails when the securing means is in its operative or in- 85 operative position.

In testimony whereof I affix my signature.

JOHN SITKO.
